(57) **CLAIM**

The ornamental design for a wedge for tile installation device, as shown and described.

DESCRIPTION

FIG. 1 is a front perspective view of a wedge for tile installation device;

FIG. 2 is a right side elevation view of the wedge for tile installation device shown in FIG. 1, which includes left-right symmetry;

FIG. 3 is a top plan view of the wedge for tile installation device shown in FIG. 1;

FIG. 4 is a bottom plan view of the wedge for tile installation device shown in FIG. 1;

FIG. 5 is a front elevation view of the wedge for tile installation device, as shown in FIG. 1; and,

FIG. 6 is a rear elevation view of the wedge for tile installation device, as shown in FIG. 1.

The broken lines in the drawings illustrate portions of the wedge for tile installation device and form no part of the claimed design.
